TOY VEHICLE

Robert Gluth and Willy Kellermann, Nuremberg,
Germany; said Gluth assignor to said Kellermann

Application May 21, 1937, Serial No. 144,083
In Germany November 11, 1935

8 Claims. (Cl. 46—111)

This invention relates to toy vehicles and more especially to toy vehicles operated by means of a spring-driven clockwork which, in addition to furnishing the driving power, is utilized to operate a device for producing operating noises, signals or similar sounds.

Our invention essentially consists in a special and advantageous novel construction of the aforesaid sound producing device, said construction comprising an axle to which rotation as well as periodical swinging motion is imparted by said clockwork, and a clapper mounted on said axle, said clapper coming periodically in contact with the casing of the toy-vehicle to produce the desired operating noises, signals or similar sounds.

By constructing the sound producing device in the manner indicated the entire construction of said device will be simplified at the same time attaining proper and reliable operation thereof. The present construction furthermore has the advantage that the spring-driven clockwork and the sound producing device may be made in the form of a unitary structure and that the casing of the toy-vehicle may be used as the sounding member proper. In this manner, special sound producing surfaces may be dispensed with, as the hollow casing of the toy-vehicle will itself form the sounding member. Besides, our novel sound-producing device will require solely an additional axle which may easily be operatively connected with the clockwork and merely be provided with a clapper adapted to come periodically into sliding contact with said casing. Thus, by our present construction any further sound producing member will be dispensed with and, in addition, said axle may be easily and conveniently assembled with the clockwork during manufacture.

In the accompanying drawing we have represented two forms of construction of our novel toy-vehicle and more particularly of our novel sound producing device.

The first form of construction which comprises the aforesaid axle and clapper and control means in the form of a cam and a tension spring for imparting, in addition to the rotary motion, a periodical swinging motion to said axle, is shown in Figs. 1 and 2. A modification is shown in Figs. 3, 4 and 5.

In the drawing:

Fig. 1 is a longitudinal vertical section through a vehicle embodying the preferred form of the invention, certain of the operating gearing being shown diagrammatically;

Fig. 2 is an elevation of the invention of Fig. 1 apart from the vehicle;

Fig. 3 is a view similar to Fig. 1 of a modified form of the invention with the sounding means in the silent position;

Fig. 4 is a view similar to Fig. 3 with the sounding means in the sounding position; and

Fig. 5 is a plan view of the device of Fig. 3 with parts broken away to disclose the operating means.

Referring more particularly to the several figures of the drawing, according to Figs. 1 and 2 the rear axle together with the rear-wheels of the toy-vehicle is driven by the intermediary of a gear-wheel or pinion 2 and the further gear-wheel 3 from the main driving wheel 1 of the clockwork which is mounted within the casing 16 of the toy-vehicle. The gear-wheel 3 further serves to drive the axle 8 by way of a pinion 4 at one end of said axle, the other end of this axle carrying a crown-wheel 6 which is positioned at the outside of the casing 21 for the clockwork and in mesh with a small gear-wheel or pinion 7, the latter being mounted on the axle 8 which is directed longitudinally with respect to the vehicle, said latter axle being provided at its front end with a toothed wheel 9 or clapper similar to a crown-wheel. The axle 8 is mounted within a bearing-flap 20 on the casing 21 of the clockwork only at the rear end thereof to permit swinging of the axle 8 in a vertical plane. The axle 8 is also suspended by means of a spring 10 from a bracket 11 fast on the casing 21 of the clockwork.

The axle 8 furthermore is under control of a cam 12 mounted on the winding stem of the clockwork, said cam imparting downward swinging motion to said axle 8 against the action of the spring 10 but periodically permitting the latter to swing the axle 8 upwardly with the effect that said toothed wheel or clapper 9 will periodically be pressed against the casing of the toy 40 and again be retracted therefrom so that said toothed wheel or clapper 9 upon contacting with the wall of said casing will produce a sound imitating that of an automobile-horn.

In order to more properly generate this sound, the casing of the toy may be provided at a place of contact with said clapper 9 with corrugations, ribs, notches, projections, depressions 13 or the like.

The clockwork together with the axle 8 and the clapper 9 may conveniently be made as a unit and mounted as such on the base-plate of the toy-vehicle so that said clockwork and axle will be entirely covered up by said casing with which said

clapper 9 comes periodically into sliding contact for producing said sound.

The second form of construction of our new toy-vehicle represented in Figs. 3, 4 and 5 comprises a spring-driven clockwork 1 mounted on the base-plate 15 of the toy-vehicle, said clockwork having its winding-stem at 1' and serving for driving the axle 2 for the rear-wheels 3. One of the gear-wheels of the clockwork 1 further serves for driving an axle 5 by way of a pinion 4 at one end thereof, the other or outer end of said axle 5 carrying the crown-wheel 6 meshing with the pinion 7 on the axle 8' which is positioned laterally of the clockwork and in longitudinal direction of the toy-vehicle. The front end of said axle 8' carries the toothed wheel or clapper 9' having the form of a crown-wheel. At its rear end said axle 8' is mounted somewhat loosely in a bearing 13' which is preferably formed by a flap bent out of the casing of the clockwork. Said axle 8', in addition, is guided at a point nearer to its front end in a slotted bearing 11' permitting upward and downward swinging of said axle. On the winding stem 1' of said clockwork there is mounted the cam 12' which upon operation of said clockwork will impart downward swinging motion to said axle 8' and the clapper 9' mounted thereon.

Engagement between the crown-wheel 6 and the pinion 7 on the axle 8' is such that rotation and periodical upward and downward swinging motion is imparted to said axle 8' and the clapper 9' thereon. In this case the casing 14 of the toy may likewise be provided at the place of contact with said clapper 9' with corrugations, ribs, notches or the like as indicated at 13.

Upon rotation of the crown-wheel 6 said axle 8' and therewith said clapper 9' will be swung upward and moved into slight contact with the casing 14 and the corrugations or the like at 13 thus producing the desired sound. The crown wheel 6 rotates in the direction of the arrow and rotates the pinion and the axle 8'. Under the influence of this rotation, the loosely mounted axle 8' is, of course, vibrated and as the bottom and sides of the guide 11' prevent downward or lateral movement, it is swung upwards on its pivot 13' until further upward movement is prevented by the clapper 9' contacting the corrugation 13. This sound may further be improved by providing said clapper 9' on the axle 8' with an eccentric weight 10' which by action of its centrifugal force will periodically increase the contact or sliding pressure between said clapper 9' and said casing 14. While the upward swinging motion of said axle 8' and therewith the contact of said clapper 9' with said casing is effected by the rotation of said crown-wheel 6, the downward swinging motion of said axle 8' and said clapper 9' is brought about by the cam 12' with the effect of temporarily or periodically interrupting the produced sound.

The casing 14 which covers up the clockwork 1 is mounted preferably loosely or with the intermediary of a sound insulating layer on the base-plate 15 of the toy-vehicle. The casing 14 thus will act practically as the sounding member of a bell thus improving the resonance of the sound produced during the sliding contact between clapper 9' and casing 14.

While we have shown and described herein a rotating axle 8 and clapper 9, which in addition to its rotation may be swung upward and downward

in a vertical plane, it will also be possible to cause swinging of said axle and clapper in another plane, for instance in a horizontal plane.

We claim:

1. A toy-vehicle comprising a casing, a spring-driven clockwork and a sound-producing device to be operated by said clockwork, said sound-producing device consisting of an axle, of mechanism for imparting a combined rotary and periodical swinging motion to said axle from said clockwork, and of a clapper mounted on said axle and adapted to produce a sound when in sliding contact with said casing. 5

2. A toy-vehicle as specified by claim 1 comprising a spring interposed between said axle and some point fixed with respect to the toy-vehicle, said mechanism including a cam driven by said clockwork and adapted to impart said periodical swinging motion to said axle in co-operation with said spring to cause said clapper to come periodically into sliding contact with said casing to periodically produce said sound. 10

3. A toy-vehicle as specified by claim 1, comprising a bearing for said axle at one end thereof, a further slotted bearing for said axle nearer the other free end thereof, both of said bearings permitting said combined rotary and periodical swinging motion of said axle, said mechanism including a pinion mounted on said axle in mesh with a gear-wheel of said clockwork, to impart 20 said rotary motion to said axle and said clapper as well as said swinging motion in the direction of said casing, and a cam driven by said clockwork and adapted to impart said periodical swinging motion to said axle, in a direction away 25 from said casing.

4. A toy-vehicle as specified by claim 1, and an eccentric weight operatively associated with said axle and clapper to periodically vary by action of its centrifugal force the contact-pressure between said clapper and said casing to produce a periodical varying sound. 30

5. A toy-vehicle as specified by claim 1, comprising a spring interposed between said axle and some point fixed with respect to the toy-vehicle, 40 said mechanism including a cam driven by said clockwork and adapted to impart said periodical swinging motion to said axle in co-operation with said spring to cause said clapper to come periodically into sliding contact with said casing to periodically produce said sound, and an eccentric weight operatively associated with said axle and said clapper to periodically vary by action of its centrifugal force the contact-pressure between said clapper and said casing for producing a periodically varying sound during times of contact between said clapper and said casing. 45

6. A toy-vehicle as specified by claim 1, in which said casing at a place of contact with said clapper is provided with corrugations or the like to intensify the sound produced by sliding contact between said clapper and said corrugations. 50

7. A toy-vehicle as specified by claim 1, in which said clapper is provided with a toothed periphery. 55

8. A toy-vehicle as specified by claim 1, in which said casing is mounted loosely with respect to the body of the toy-vehicle to increase the sound-producing effect and the resonance of said casing during rotation of said clapper in contact therewith. 60
